[57] ABSTRACT

A parasitic director array for use with active dipole sections of an antenna. In antennas having a relatively broad operating frequency range which may be of the order of 2:1 (i.e., wherein the operating frequency of the high end of the range is two or more times as great as the operating frequency at the low end of the range). The director array which is comprised of at least first and second conductive plates arranged in closely spaced fashion and staggered along the antenna mounting rod so that the conductive plates extend on opposite sides thereof operate as individual director elements near the high end of the operating band, while operating effectively as a single director element near the low end of the band so as to improve directivity and gain characteristics over the entire operating frequency band of the antenna active element region.

DIRECTOR ARRAY FOR ANTENNAS

This is a continuation of application, Ser. No. 23,232, filed Mar. 25, 1970, now abandoned.

The present invention relates to antennas and more particularly to a director array for use with antenna active element arrays to improve the directivity and gain characteristics over the entire operating frequency band in which the frequency at the high end of the band is two or more times as great as the frequency at the low end of the band.

There exists a wide variety of antennas capable of providing reasonably good gain and directivity characteristics over a substantially large operating frequency range. For example, it is well known to employ Yagi-type antennas and logperiodic type antennas for television reception since such antennas have characteristics of providing reasonably good gain and directivity characteristics over substantially broad operating frequency bands. The television frequency ranges consist of low band VHF which extends from 54-88 megacycles; the upper VHF band which extends from 174-216 megacycles; and the UHF band which extends from 470-890 megacycles. Numerous efforts have been made to improve gain and directivity characteristics of such antennas. One typical approach is that of providing parasitic arrays comprised of one or more parasitic elements of either the director or reflector type which may either be interspersed amongst the active elements or, alternatively, placed in front of the front end of an active element array. Also, both techniques have been incorporated within an individual antenna array.

One prior art array which has been employed to improve gain and directivity characteristics is comprised of one or more conductive plates arranged at substantially equal spaced intervals along the antenna mounting rod and in front of the front end of the antenna active element array. These elements, in one preferred form, are comprised of substantially circular shaped discs formed of a conductive material and whose dimensions are selected to cause the individual conductor plates to operate as director elements for the purpose of improving the radiation pattern and hence the gain and directivity characteristics of the antenna. This technique has been employed with some success for use with antennas designed to receive television signals within the UHF range. The dimensions of such conductor plates and their interval spacing have been found to be rather critical in that the interval spacing between adjacent elements have been found to control the effectiveness of these elements over the operating frequency band. The dimensions of the conductor plates have also been found to control the effectiveness of the director elements to a very significant degree. For example, it has been found that the closer spacing of the conductive plates results in improved gain toward the high end of the operating frequency band. Likewise, the dimensions (i.e., diameters) of the individual conductive plates control the effectiveness of the director elements such that the elements of decreased diameter operate more effectively near the high end of the operating frequency band while the increasing diameter of the elements cause greater effectiveness near the lower end of the operating frequency band.

Still further investigation of director dimensioning and spacing has shown that it is a practical impossibility to design a director array which is capable of improving to the same degree the radiation pattern over the entire operating frequency range. As a result of this, the design of such a director array becomes a compromise wherein the spacing between director elements and the dimensions (i.e., size) of the director elements themselves are normally chosen so as to yield the greatest improvement in radiation pattern at an operating frequency which lies slightly above the middle range of the operating frequency band. For example, in antennas designed for UHF reception whose operating frequency range extends from 470-890 megacycles, it has been found to be most preferable to dimension and space the director elements so as to yield the optimum improvement in the antenna radiation pattern at an operating frequency in the immediate region of about 800 megacycles. Experimentation has shown that the deterioration of the radiation pattern decreases for operating frequencies between the mid range and the high end of the operating frequency band. Deterioration in the improvement of the radiation pattern from the mid range value to the low end of the operating frequency band occurs at a much more significant rate. Although the obvious adjustment of director element and interval spacing to provide optimum improvement in the radiation pattern at a frequency well below mid range has been attempted, experimentation of antennas utilizing this design approach has shown that the deterioration in the radiation pattern begins to drop off rapidly so that the TV reception at the high end of the operating frequency band is substantially affected by this design change resulting in the use of director arrays employing the design criteria first described hereinabove.

The present invention is characterized by providing a director array for use with antenna active element sections which is capable of providing significant improvement in the radiation pattern of the antenna over substantially the entire operating frequency band as compared with antennas employing conventional director arrays of the type described hereinabove.

Whereas the director array of the present invention, in the preferred form, is utilized with active element sections of antennas of the log-periodic type, it should be understood that other active element arrays may be employed with equal success in conjunction with the director array of the present invention.

In one preferred embodiment the active element section is comprised of a log-periodic type active element array having a plurality of spaced dipole elements whose arms are either straight or V'eed and whose dipole arms and spacing between adjacent dipoles decreases in log-periodic fashion from the rear of the array toward the front. The active element section is preferably mounted upon (or in some cases, two) mounting rod, the forward end of which (or an extension thereof) supports the director array. Preferably, the antenna feed point for connection to a receiver (or transmitter) is coupled to the active element section by means of a feeder harness. The feeder harness is preferably transposed between adjacent dipole elements within the array.

The director elements are mounted upon the front end of the antenna array in front of the feed point such that the director elements extend in alternating fashion to opposite sides of the principal axis and lie substantially in a horizontal plane and are further substantially coplanar with the antenna active elements. As an alternative arrangement the director elements may alternately extend above and below the principal axis and yield good operating results. The top-bottom alternation also works well. The spacing intervals between adjacent conducting plates and the dimensions of each plate are chosen so as to provide a substantially optimum radiation pattern in the vicinity of 890 megacycles which lies at the top end of the UHF operating band. The operating characteristics of the director array are such that near the high end of the operating frequency band each of the director elements are spaced by a distance sufficient to cause each of the elements to operate as separate elements which appear as two separate rows of small parasites. When the antenna is operating in the low frequency mode, adjacent staggered conducting plates operate effectively as a single conductive plate which gives the effective characteristic of appearing as a single slightly tilted and larger conductive member. Thus, the director array provides an improved radiation pattern over substantially the entire UHF operating frequency band as compared with conventional techniques in which conductive plate director arrays are capable of improving the radiation patterns over only a small portion of the entire UHF frequency band. For example, the improvement in gain has been found to be double that of the conventional design.

It is therefore, one object of the present invention to provide a novel director array comprised of a plurality of staggered conductive plates arranged at the front end of an antenna active element section wherein the spacing interval between conductor plates and the dimensions of the plates themselves act to provide significantly improved radiation patterns over the entire operating frequency band.

This, as well as other objects of the present invention will become apparent when reading the accompanying description and drawings in which:

FIG. 1a is a top plan view of one preferred conductive plate which may be employed in the director array of the present invention.

FIGS. 1b and 1c are side and end views respectively of the conductive plate of FIG. 1a.

FIG. 2 is a plan view showing an alternative preferred embodiment of a conductive plate which may be employed with equal success in the director array of the present invention. FIGS. 2b and 2c are side and end views respectively of the conductive plate of FIG. 2a.

FIG. 3a shows a top plan view of an antenna array employing a director array designed in accordance with the principles of the present invention.

FIG. 3b shows an elevational view of the antenna array of FIG. 3a.

FIG. 4a shows a top plan view of another antenna array employing the director array of the present invention.

FIG. 4b is an elevational view of the antenna array shown in FIG. 4a.

FIGS. 5 and 6 are perspective views showing other alternative embodiments of the conductor plates of FIGS. 1 and 2.

FIG. 1a shows a conductive plate 10 which may be employed in the director array, to be more fully described, which plate 10 is formed of a relatively thin conductive sheet 11 (preferably aluminum) having tapered sides 12 and 13, which curved sections are truncated at 14. The sides 12, 13 and 14 terminate in a continuous flange 15, shown best in FIG. 1b. The major portion of plate 11 is provided with a π shaped reinforcing rib 16. A square shaped slot 17 is formed at the inward end of plate 10 for joining to the antenna supporting rod in a manner to be more fully described.

A pair of C-shaped openings 18 and 19 are formed near the inboard end of plate 10 and the portions of 11a and 11b (see FIGS. 1b and 1c) defined by the openings are bent inwardly in the manner shown best in FIG. 1c to form a pair of mounting arms each provided with an aperture 19a and 19b respectively, for receiving a fastening member (not shown in FIGS. 1a-1c) to firmly secure each plate to the antenna supporting rod.

FIGS. 2a-2c show an alternative conductor plate 20 formed of a substantially thin sheet 21 of conductor material (preferably aluminum) which sheet has a substantially rectangular shape. The outboard end thereof is provided with a C-shaped reinforcing rib 22, while the central portion thereof is provided with a substantially π -shaped reinforcing rib 23. The top and bottom sides 24 and 25 each terminate in a downwardly depending flange 24a and 25a respectively, to further reinforce the plate.

A substantially square shaped slot 26 is provided at the inboard end of conductive plate 20 to embrace the antenna supporting rod in a manner to be more fully described. A pair of C-shaped openings 27 and 28 are provided near the inboard end of the conductor plate and the plate portions 21a and 21b defined by these openings are bent downwardly in the manner shown best in FIG. 2c to form a pair of mounting arms each provided with openings 29a and 29b, respectively, for receiving fastening means (not shown in FIGS. 1a-1c) for the purpose of securing the conductive plate to the antenna supporting rod.

FIGS. 3a and 3b show an antenna array 30 employing a director array which may utilize the conductive plates 10 or 20 described hereinabove. The antenna array 30 is comprised of a VHF section 31, a UHF section 32 and a director array 33.

The VHF section is comprised of a pair of elongated conductive supporting members 34 and 35 mechanically joined to one another and electrically insulated from one another by mounting brackets 36a-36c. These brackets maintain members 34 and 35 in spaced parallel fashion as shown best in FIG. 3b. A U-bolt assembly 37 is firmly secured to members 34 and 35 and is provided for the purpose of mounting the antenna to a suitable vertically aligned supporting mast.

The VHF section 31 which is designed to receive (or transmit) television signals lying in both the low band and high-band VHF is comprised of a plurality of dipole elements 38a-38b through 41a-41b which are of electrical lengths and are arranged at spaced intervals selected to provide optimum and preferably substantially uniform gain over both low band and high band

VHF. Each of the dipole elements is mounted to an associated one of the conductive members 34 and 35 by bracket means 42a-42g. These brackets electrically connect their associated dipole arms in alternating fashion to members 34 and 35 which thereby act as the equivalent of a transposed feeder harness. Each of the elements has associated therewith an arrow such as, for example, arrow 43 which indicates the direction in which its associated dipole arm may be folded toward members 34 and 35 to reduce the overall antenna size during shipment. These arms are then unfolded in the reverse direction so as to assume the solid line positions shown in FIG. 3a.

The dipole arms 40a-41b utilize capacitive elements 44a-44 respectively, for the purpose of improving reception over the entire VHF operating frequency bands. These capacitive elements are described in greater detail in copending application, Ser. No. 523,447, filed Jan. 27, 1966 and assigned to the assignee of the present invention. Since a detailed description is set forth in this copending patent application of such structures will be set forth herein for purposes of simplicity.

The VHF section 31 is further provided with parasitic structures 41a-41b, 45a-45b and 46a-46b which parasitic structures are provided for improving the radiation pattern of the antenna during VHF reception (or transmission). The elements 45a and 45b are secured by means of a bracket 47 to a short supporting arm 48 secured between elongated members 34 and 35 by means of supporting bracket 36a and a second bracket 49. The structures 46a-46b and 41a-41b are mounted by brackets 50 and 51 to an elongated rod 52 positioned between elongated members 34 and 35 and secured in this position by the supporting brackets 36b and 36c, respectively. All of the parasitic elements within the VHF section are electrically insulated from the array active elements and are provided solely for the purpose of improving the directivity characteristics of the antenna. These elements are likewise capable of being folded inwardly toward the antenna principal axis to facilitate handling of the antenna during assembly, shipping and mounting thereof.

The UHF section 32 of antenna array 39 is comprised of a plurality of wire elements 53a-53b through 58a-58b which form a UHF section of active elements electrically joined to one another by means of a transposed feeder harness 59 whose take-off point is at terminals 59a and 59b. The spacing and electrical length of the active dipoles 53a-53b through 58a-58b is such as to provide high and substantially uniform gain over the entire UHF range. As can best be seen in FIG. 3b, the transposed feeder harness 59 has its separate lines 59c and 59d electrically coupled to the right-hand most ends of elongated conductive members 34 and 35 and are secured thereto by suitable fastening means 60a and 60b, respectively. As was previously described, the conductive members 34 and 35 effectively act as a transposed feeder harness, a detailed description of which is set forth in U.S. Pat. No. 3,108,280 and is shown best in FIG. 2 thereof.

As can best be seen in FIG. 3b the feed point of the transposed feeder harness may be provided with butterfly type fasteners such as 61 to facilitate connection of the down-lead from the antenna to the receiver (or

transmitter) facility not shown in the figures. The connecting leads 62, shown in dotted fashion, may be inserted through a strain relief member 63 secured to supporting rod 52 for the purpose of relieving strain upon the connecting terminals 59a and 59b.

Each of the dipole arms 53a-58b are mechanically secured to and electrically insulated from the supporting rod 52 by means of substantially similar brackets 64a-69.

10 The design of both the UHF and VHF sections are preferably of the log-periodic type which design is described in detail in the above mentioned U.S. patents and copending application and will not be described herein for purposes of simplicity, however, it should be understood that the director array 33, to be more fully described herein, may be utilized with other VHF and UHF sections or with UHF sections alone which active element sections may be of any suitable design.

20 The director array 33 is comprised of a plurality of conductive plates such as, for example, plates 10a-10h each of which is substantially identical in configuration to the plate 10 shown in FIGS. 1a-1c. As can clearly be seen from FIG. 3a, plates 10a-10h are arranged in staggered fashion so that alternating plates 10a, 10c, 10e and 10g each extend toward one side of supporting rod 52 while the remaining plates 10b, 10d, 10f and 10h are interspersed amongst plates 10a, 10c, 10e and 10g and extend to the opposite side of supporting rod 52. Each 30 of the plates is positioned relative to supporting rod 52 (which preferably has a rectangular cross-sectional configuration) so that their inboard slots 17 (see FIG. 1a) embrace rod 52, enabling the supporting arms 11a and 11b to be secured to the upper and lower horizontal surfaces of the supporting rod by fastening means 64.

40 In operation, the director array 33 is designed to significantly enhance the reception (or transmission) characteristics of the antenna UHF section over substantially the entire UHF range (470-890 megacycles). The intervals between conductive plates 10a-10h are selected to be substantially small and these intervals are no greater than $1/10\lambda$ wherein λ is the wavelength of the uppermost frequency of the UHF band which is usually of the order of 890 megacycles. The closest spacing interval is preferably no smaller than $\lambda/20$. The dimensions, shape and thickness of the conductive plates are adjusted to be resonant at approximately 900 50 MC or the top of the UHF band. Preferably, each of the conductive plates is identical in size and configuration although some deviation may be made for purposes of trimming the antenna design to optimize the radiation pattern over the entire UHF range. As was previously 55 described, the maximum limit of the relatively close spacing intervals between adjacent conductive plates is sufficient to cause each plate to operate effectively as a single conductive plate at the upper end of the UHF range. Spacing much smaller than $\lambda/20$ will cause adjacent pairs of plates such as, for example, pair 10g and 10h to operate as a single conductive plate whose effective electrical length will be too large and therefore ineffective at the upper end of the UHF range.

60 By limiting the maximum amount of spacing between adjacent plates, the operation of the director array near the low end of the UHF range is such as to cause adjacent pairs of plates such as plates 10g and 10h, for ex-

ample, to operate effectively as a single conductive plate whose electrical length is proper at the lower end of the UHF band to optimize the radiation pattern in this range. Any larger spacing would render adjacent conductive plates incapable of operating effectively as a single conductive plate and thereby greatly deteriorate the effectiveness of the director array.

FIGS. 4a and 4b show a somewhat modified antenna array 70 comprised of a VHF section 71, a UHF section 72 and a director array 73. Similar elements as between the embodiment FIGS. 4a-4b and 3a-3b are designated by like numerals. For example, the VHF section includes a pair of elongated conductive elements 34 and 35 joined together by supporting brackets 36a-36c and being further provided with a U-bolt assembly 37 for mounting upon an antenna supporting mast. The VHF section is provided with a plurality of dipole arms 74a-74 through 76a-76b rotatably mounted by suitable brackets 77a-77f to selective ones of the elongated conductive members 34 and 35 which operate as a transposed feeder harness in the same manner as was previously described. In addition to electrically connecting the dipole arms to elements 34 and 35 these brackets permit folding of the arms toward the principal axis of the antenna in the direction shown by the arrows immediately adjacent the outboard ends of each arm. For example, arrow 78 indicates that arm 76a folds counterclockwise relative to its bracket 77e while arm 75a folds clockwise as shown by arrow 75 to align with the principal axis of the antenna array.

When the dipole arms are folded outwardly to their proper position, as shown in solid line fashion in FIG. 4a, it can be noted that the VHF section is comprised of dipoles whose arms are V'ed forward toward the front end of the antenna.

It should be noted that arms 75a-76b are provided with capacitive elements 78a-78d, respectively, which capacitively couple the inboard and outboard sections of the dipole arms for improving the overall gain of the antenna throughout the entire VHF upper and lower band. The VHF section 71 is further provided with a parasitic structure comprised of arms 79a and 79b joined at their inboard ends by means of a bracket 80 to supporting rod 52 which, in turn, is positioned between elongated members 34 and 35 and is supported in this position by means of brackets 36b and 36c. The parasitic structure 79a-79b is provided with capacitive elements 78e and 78f, respectively, which operate in a manner similar to the capacitive elements 78a-78d in that the inboard and outboard sections of arms 79a and 79b are either loosely or tightly (electrically) coupled to one another, depending upon the operating frequency of the antenna at any given moment.

The UHF section 72 of antenna array 70 is comprised of a plurality of wire-type arms or elements 80a-80 through 85a which are arranged in staggered fashion on opposite sides of the antenna principal axis and are selectively connected to the upper and lower elongated arms 34 and 35 in a staggered fashion so as to utilize the arms 34 and 35 as an effective transposed feeder harness in the same manner as these arms are utilized in the VHF section 71 and in the VHF section 31 of antenna array 30 shown in FIG. 3a. The feed point for the active element arrays is at the front end of the UHF array 72 and is electrically coupled by suitable

conductors 86 to a bracket 87 provided with butterfly fasteners 88 for coupling the feed point to a receiver (or transmitter) facility not shown in the figures. The spacing intervals of the dipole arms and the length of the dipole arms in both the VHF section 71 and UHF section 72 are in accordance with log-periodic design described in any of the above mentioned copending applications and U.S. patents in order to enhance the gain of the antenna over both the low band and high band VHF and the UHF ranges.

Supporting arm 52 extends forward of the feed point connectors 88 and has coupled thereto a plurality of conductive plates 20a-20f which may, for example, be of the type shown as conductive plate 20 in FIGS. 2a-2c. The conductive plates are arranged along the forward end of supporting arm 52 in a staggered fashion wherein plates 20a, 20c and 20e extend to one side of the antenna principal axis while plates 20b, 20d and 20f extend to the opposite side of the principal axis. The slots 26 (see FIG. 2a) of each conductive plate are positioned to surround supporting rod 52 which preferably has a rectangular shaped cross-sectional configuration. The mounting arms 21a and 21b (see FIGS. 4a, 4b, 2b and 2c) are secured to the upper and lower surfaces of supporting rod 52 by suitable fastening means 8-9.

All of the conductive plates are substantially identical in size and configuration although some departure from this design may be employed to optimize the operating characteristics of the antenna array. The spacing intervals and dimensions of the conductive plates are selected in the manner previously described so as to enable adjacent pairs of conductive plates, for example, plates 20e and 20f, to operate effectively as a single conductive plate near the low end of the UHF range while operating as individual conductive plates near the upper end of the UHF range so as to provide significantly improved radiation patterns over the entire UHF range. In operation near the high end of the UHF range the conductive plates operate effectively as two pairs of arrays (one array comprised of conductive plates 20a, 20c and 20e and the other array being comprised of plates 20b, 20d and 20f) each of which is spaced apart sufficiently to allow each plate to operate independently of every other plate to enhance the operating characteristics of the antenna. Near the low end of the UHF range the plates are spaced closely enough and are individually dimensioned so that each pair of adjacent plates, for example, plates 20e and 20f, operate effectively as a single conductive plate whose dimensions are such as to enhance the operating characteristics of the antenna in the low end of the UHF range.

FIGS. 5 and 6 show additional preferred embodiments of the conductive plates which may be employed with equal success in the antenna arrays previously described. The embodiment 90 of FIG. 5 is comprised of a conductive plate having a tapered outboard end 91. The bent portions 92 and 92a form the mounting arms as was previously described.

The conductive plates 93 of FIG. 6 is a truncated circular configuration wherein less than half of the entire circle is removed. The arms 94 and 94a which act as the supporting arms, are pivotally mounted to the support 95 to enable each conductive plate to be pivoted

inwardly toward the supporting arm to reduce the overall volume of space required for stripping the antenna. When installing the antenna the plates are pivoted outwardly to assume their operating position. The forward ends of arms 94 and 94a are tapered to 5 cooperate with a pair of ears 96 and 96a projecting slightly upwardly from and integrally formed with a small metallic plate 97, wherein like plates are mounted on opposite surfaces of support 95. Each of the pair of ears 96 and 96a define a gap 98 10 therebetween. By rotating the truncated disc 93 in a direction shown by arrow 99, the tapered forward end of arms 94 and 94a "snap" into position in the gap 98 formed between the slightly upwardly bent ears 96 and 96a so as to lock the truncated disc 93 in position whereby the disc is oriented at an angle of substantially 90° relative to support 95.

It can be seen from the foregoing description that the present invention provides a novel director array for use with UHF or combined UHF-VHF antenna arrays in which the director elements are arranged in staggered fashion on opposite sides of the antenna array principal axis and are so spaced and dimensioned as to enhance the operating characteristics over the entire UHF operating range by a significant amount as compared with conventional techniques. Although the antenna array 30 is described as employing conductive plates of the type shown in FIG. 1a, and the antenna array 70 is described as employing conductive plates of the type shown in FIG. 2a, it should be understood that either type of conductive plate may be used in either array. Also, the arrays may be employed with the UHF arrays alone. It should further be understood that a lesser or greater number of conductive plates may be employed in the director array as long as a minimum of at least two such director elements each extending to opposite sides of the antenna array principal axis are employed so as to enhance the operating characteristics of the antenna.

Although this invention has been described with respect to its preferred embodiments, it should be understood that many variations and modifications will now be obvious to those skilled in the art, and it is preferred, therefore, that the scope of the invention be limited not by the specific disclosure herein, but only by the appended claims.

The embodiments of the invention in which an exclusive privilege or property is claimed are defined as follows:

1. A director array for use in antennas having an active element section mounted along a principal axis and designed to operate over a predetermined frequency range;

said active element section having a feed point coupled to a feeder harness at the front end of said active element section, said feeder harness coupling all of the active elements to said feed point, the active elements lying substantially within a plane; said director array being positioned in front of said active section and said feed point and being comprised of mounting means axially aligned with the principal axis of said active element section, and at least first and second substantially flat conductive plates secured to said mounting means and extending in diametrically opposite directions from the

principal axis of said active element section and arranged in staggered spaced parallel fashion, said conductive plates being substantially mirror images of one another relative to an imaginary plane of symmetry passing through said principal axis and the planes of said plates being perpendicular to the plane in which said active elements reside; the spacing between adjacent plates being in the range from no greater than $\lambda/10$ to no less than $\lambda/20$ where λ is the wavelength corresponding to the highest frequency of the operating frequency range.

2. The director array of claim 1 wherein said conductive plates are each tuned to resonate at a frequency near the high end of said operating frequency range and being spaced no closer than $\lambda/20$ wavelengths apart where λ is the wavelength of the upper end of said frequency range.

3. The director array of claim 2 wherein said conductive plates are spaced apart no greater than $\lambda/10$.

4. The director array of claim 3 wherein said conductive plates are each tuned to resonate at a frequency near the high end of said operating frequency range and being spaced no closer than $\lambda/20$ wavelengths apart where λ is the wavelength of the upper end of said frequency range.

5. The director array of claim 1 further comprising a support arm for supporting said conductive plates:

each of said conductive plates being provided with a pair of mounting arms for pivotally mounting said conductive plates to said support arm; at least one of said mounting arms having a tapered forward end; a pair of slightly upwardly bent ears being provided along said support adjacent one of said arms and defining a gap therebetween to embrace the forward tapered end of said one of said mounting arms and thereby lock said conductive plate in the operating position.

6. The array of claim 1 wherein each of said plates is a truncated circular disc.

7. The array of claim 1 wherein each of said plates has a substantially rectangular shaped configuration.

8. The array of claim 1 wherein each of said plates has a tapered configuration wherein the widest portion thereof is joined to said support and wherein the narrow end of the tapered plates projects outwardly from said support.

9. The array of claim 1 wherein said plates are arranged in alternating fashion to lie respectively above and below said principal axis.

10. The array of claim 1 wherein said plates are arranged in alternating fashion to lie respectively to the left and to the right of said principal axis.

11. A director array for use in antennas having an active element section mounted along a principal axis and designed to operate over a predetermined frequency range;

said active element section having a feed point coupled to a feeder harness at the front end of said active element section, said feeder harness coupling all of the active elements to said feed point, the active elements lying substantially within a plane and extending outwardly from and transverse to the principal axis;

said director array being positioned in front of said active section and said feed point and being comprised of a first plurality of substantially identical flat conductive plates arranged in spaced parallel fashion and extending outwardly from one side of the active element section principal axis; 5
 a second plurality of substantially identical flat conductive plates being arranged in spaced parallel fashion and extending outwardly from the opposite side of said principal axis; 10
 each of said second plurality of conductive plates being interspersed with said first plurality of conductive plates whereby said first and second pluralities form a staggered array along said principal

axis; 15
 the spacing between adjacent ones of said first and second plates being equal and the planes of said plates being perpendicular to the plane in which said active elements reside; 20
 the spacing between adjacent plates being in the range from no greater than $\lambda/10$ to no less than $\lambda/20$ where λ is the wavelength corresponding to the highest frequency of the operating frequency range.

12. The director array of claim 11 wherein said conductive plates are spaced apart no greater than $\lambda/10$.
